Attorney

UNITED STATES PATENT OFFICE.

ART HADLEY, OF PROVIDENCE, RHODE ISLAND, ASSIGNOR TO THE HADLEY COMPANY,
OF PROVIDENCE, RHODE ISLAND.

WRIST-WATCH-STRAP CONNECTER.

Application filed April 7, 1926. Serial No. 100,310.

This invention relates to certain new and useful improvements in wrist watch strap connectors and the primary object thereof is to provide a simplified form of connector 5 of this type which can be assembled without the use of solder and which can thus be more economically and quickly produced.

The invention further aims to provide a connector of this type which is stronger and 10 of greater durability than the soldered forms of connectors.

In the drawings:—

Figure 1 is a plan view of the invention applied to a wrist watch and strap;

15 Figure 2 is an enlarged section taken on line 2—2 of Fig. 1, and

Figure 3 is a like view on line 3—3 of Fig. 1.

In proceeding in accordance with the present invention, a blank is initially shaped to 20 form a body 1 having hooks 2, 2 at its ends the body being curved at 3 to conform to the watch case periphery, while the hooks 2 are formed to engage over the usual bars 4 secured to diametrically opposite sides of 25 the watch case. On the side of the body 1, opposite to the side on which the hooks 2 project, the same is formed with lugs 5 having eyes in which the ends of a rod or 30 pin 6 are received. The center of the rod 6 is formed with a circular V-groove 7. A thin tube 8 is received over the rod 6 and is formed of a length to be received in the space between the lugs 5 and to have its 35 ends abut the inner faces of the lugs. With the rod and tube thus assembled, as shown in Fig. 3, a teat 9 is punched inwardly from the tube to engage in the groove 7. The outline of the teat is of somewhat oval form as 40 shown in Fig. 1 and due to the thin material of which the tube 8 is constructed, the teat is resiliently supported thereby and affords

a spring friction grip which is forced or snapped into the groove 7. From the foregoing it will be seen that the tube is anchored by teat 9 to pin 6 and due to the ends of the tube abutting the lugs 5 the parts are held securely assembled and against axial movement, without the use of solder.

The tubes 8 are connected to the strap ends 50 S as is well understood in the art.

Having thus described my invention, what I claim as new and desire to secure by Letters Patent is:—

1. A connector for articles having securing bars, including a body having a central part conformed to engage a side of the article and having hooks at the ends of said part to engage the bar of the article, lugs having eyes adjacent the ends of the body, a 55 rod received at its ends in the eyes and having a central circular groove, and a thin resilient tube engaged over the rod and having its ends abutting the lugs, said tube having a teat punched therefrom to form a 60 spring supported member which is of concave-convex cross section and which engages in the groove of the rod, the periphery of the member being connected throughout to the tube. 70

2. In a connector, a body having spaced lugs formed with eyes, a rod engaged at its ends in the eyes, and having an intermediate circular groove, and a thin resilient tube engaged over the rod and having its ends 75 abutting the lugs, said tube having a teat punched therefrom to form a spring supported member which is of concave-convex cross section, and which engages in the groove of the rod, the periphery of the member being connected throughout to the tube. 80

In testimony whereof I have signed my name to this specification.

ART HADLEY.
